US00D594014S

(12) **United States Design Patent**
Taylor et al.

(10) **Patent No.:** US D594,014 S
(45) **Date of Patent:** ** Jun. 9, 2009

(54) **GRAPHICAL USER INTERFACE FOR A DISPLAY SCREEN**

(75) Inventors: **Jeffrey Taylor**, Glendale, WI (US); **Ranjeeta Singh**, Glendale, WI (US); **Scott Herman**, Pewaukee, WI (US); **Diana St. John**, Germantown, WI (US); **Rodger W. Eich**, Holland, MI (US)

(73) Assignee: **Johnson Controls Technology Company**, Holland, MI (US)

(**) Term: **14 Years**

(21) Appl. No.: **29/294,787**

(22) Filed: **Jan. 28, 2008**

(51) **LOC (9) Cl.** 32-00

(52) **U.S. Cl.** D14/486

(58) **Field of Classification Search** D14/485-495; 715/700-705, 716, 727, 730, 748, 750, 751, 715/760-762, 775-781, 786, 787, 808-810, 715/832-846, 863-867, 973-977

(57) **CLAIM**

We claim the ornamental design for a graphical user interface for a display screen, as shown and described.

DESCRIPTION

FIG. 1 is a front view of the graphical user interface for a display screen, shown without the display screen for ease of illustration; and,

FIG. 2 is an additional front view of the graphical user interface for a display screen.

The ornamental design which is claimed is shown in solid lines in the drawings. The broken lines in the drawings are for illustrative purposes only and form no part of the claimed design.
